FIG. 3

FIG. 2

Des. 192,413

PAGE 3

FIG. 5

FIG. 1 is a perspective view looking from an elevated position of a combination utility yard storage shelter and above ground swimming pool showing my new design, with the storage doors partially open,

FIG. 2 is an end view thereof,

FIG. 3 is a side view thereof,

FIG. 4 is a top plan view thereof showing the door in a partially open position, and

FIG. 5 is a vertical cross-sectional view taken substantially along the longitudinal center line of the pool.

I claim:

The ornamental design for a combination utility yard storage shelter and above ground swimming pool, substantially as shown.
